UNITED STATES PATENT OFFICE.

WILLIAM A. RINGLER, OF PHILADELPHIA, PENNSYLVANIA.

LOOSE-LEAF BINDER.

Application filed September 10, 1924. Serial No. 736,858.

One of the objects of this invention is to devise a novel construction of a loose leaf binder which consists of only two parts. Each part is preferably formed from an integral piece of material, one part being formed from sheet material and the other part can be formed from sheet material or from a wire.

Another object of this invention is to devise a loose leaf binder which can be very cheaply manufactured.

With the foregoing and other objects in view as will hereinafter more clearly appear, my invention comprehends a novel construction and arrangement of a loose leaf binder.

It further comprehends a novel construction of a binder, the holder of which is of novel construction, being formed from an integral piece of sheet material, and the filler-holding member is also of novel construction and has means to co-operate with the holder to effect the locking or unlocking of such member.

Other novel features of construction and advantage will hereinafter more clearly appear in the detailed description and the appended claims.

For the purpose of illustrating the invention, I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and that the invention is not limited to the precise arrangement and organization of these instrumentalities as herein set forth.

Figure 1 is a plan view of a memorandum book in conjunction with which a loose leaf binder embodying my invention is employed.

Figure 2 is a plan view, on an enlarged scale, of a portion of the binder.

Figure 3 is a plan view similar to Figure 2 but showing the parts in a different relation to each other.

Figure 4 is a plan view, on an enlarged scale, of the fixed portion of the binder.

Figure 5 is a section on line 5—5 of Figure 1.

Figure 6 is a section on line 6—6 of Figure 2.

Figures 7, 8 and 9 are perspective views

of different forms of filler carrying members, embodying my invention.

Figure 10 is a sectional view of a loose leaf binder embodying my invention, with the filler carrying member seen in Figure 9.

The fixed binder part 2 is formed from a single sheet of material and preferably from metal. It is provided with the bottom 5 which terminates in the upwardly projecting lip 6. The bottom 5 is connected with the top 7 by means of the bent portion 8 and the marginal edge portion at the side of the top is bent downwardly and partly around the filler-retaining member 9, as at 10, see Figure 5. The free end portions of the fixed portion 2 are bent around and pressed against the back of the cover 3 and the free ends pass through apertures 11 in the cover and bottom 5 and are clinched or bent over at 12, the top 7 having openings 13 to permit a suitable tool to be passed therethrough to effect the clinching operation.

The top 7 is provided near one of its marginal edges with a plurality of slots 14, and at its opposite marginal edge with the slots 15 which are enlarged as at 16 and form a locking portion 17. The filler-retaining member 9 may have different forms of construction. In Figures 1 to 6 inclusive it consists of a wire bent to form a desired number of filler retaining loops 18 which terminate in inwardly extending hooks 19. Instead of forming the filler-retaining member 9 of wire, it can be formed from sheet material as seen in Figure 8, in which the filler retaining member 20 has the same general conformation as that seen in Figure 7.

Instead of having the hook at the free end of the loop, it can extend outwardly from the filler-retaining member at any desired locations. As shown in Figures 9 and 10, the longitudinal stretch of the filler-retaining member 21 is provided with a laterally extending locking member 22 and the loop terminates in a straight end without a hook. This end extends into an opening 23 in the casing 24 which is of the same formation as the member 7 except that it is provided with the openings 23 and the slot 25 is located to co-operate with the locking member 22.

It will be clearly understood from the drawings that the fixed part 2 is formed from an integral sheet of material which is

bent so that the filler carrying member is capable of relative longitudinal movement therewith.

The filler is provided in the usual manner with apertures, so that the hooks 19 can be employed to pass therethrough, or if the hook or locking member is in the form seen in Figure 8, the free end of the loop can pass therethrough. The filler-carrying member is then turned downwardly to bring, for example, the hook 19 into the slots 16 and the filler-carrying member is then moved forwardly or to the left so that such hooks pass beneath the locking portion 17 of the fixed 10 part of the binder. When the filler-carrying member is moved rearwardly or towards the operator the hooks 19 will pass into the slots 16 so that the filler-carrying member can be moved outwardly, and any desired 15 sheet or sheets of the filler can be inserted or removed.

In the form shown in Figures 9 and 10, the hook 22 has the same function as the hook 19 and in this embodiment of my invention 20 the fixed member is provided with the openings 22 into which the free ends of the loops of the filler-carrying member extend. These locking members 22 when the filler carrying member 21 is moved longitudinally in the 25 proper direction lock with the member 24 and prevent the opening of the filler-carrying member.

My present invention can be very economically manufactured, and the parts are positively locked together when in locked position.

It will now be apparent that I have devised a new and useful loose leaf binder which embodies the features of advantage 40 enumerated as desirable in the statement of the invention and the above description, and while I have, in the present instance, shown and described a preferred embodiment thereof which will give in practice satisfactory 45 and reliable results, it is to be understood that this embodiment is susceptible of modification in various particulars without departing from the spirit or scope of the invention or sacrificing any of its advantages.

Having thus described my invention, what I claim as new and desire to secure by Letters Patent, is:

1. A two part loose leaf binder comprising a single sheet of material bent upon itself to form a top and a bottom, the free marginal edge of the bottom being upturned, a filler-carrying member around which the free marginal edge of said top is turned, to hinge said filler carrying member thereto by the said upturned edges and another portion of said sheet, said top having slots therein and said filler-carrying member having hooks movable in said slots, and, when in locked position, locking with the bottom of said top.

2. A loose leaf binder comprising a fixed member, and a movable member hinged to and having a relative longitudinal movement with respect to said fixed member, said fixed member having its end portions deflected downwardly, laterally and upwardly and connected thereby to a cover and provided with openings in its top portion to receive a clinching element to clinch said end portions between the top and bottom 75 of said member, said movable member having loops to receive the filler and having hooks which when in one position in said slots are in unlocked position and which when in another position in said slots are 80 in locked position.

3. A two-part loose leaf binder comprising a fixed and a movable member, said fixed member comprising a sheet of material bent upon itself to form a closed top, bottom and sides with the free edge of the bottom bent upwardly, said movable member being hinged between said upwardly bent portion and the juxtaposed portions of said fixed member, said movable member being 90 formed of a rod bent upon itself to form double strand hooks, the free ends of which hooks extend laterally inwardly, and said top having at opposite sides slots to provide for longitudinal sliding movement of said 95 hooks transversely to their planes.

WILLIAM A. RINGLER.
